Patented Dec. 18, 1917.

UNITED STATES PATENT OFFICE.

EUGENE C. BAECK, OF IRVINGTON, NEW YORK.

WALL-PAPER MACHINE.

1,250,761.

Specification of Letters Patent. Patented Dec. 18, 1917.

Application filed July 31, 1917. Serial No. 183,700.

To all whom it may concern:

Be it known that I, EUGENE C. BAECK, a citizen of the United States, and a resident of Irvington-on-the-Hudson, in the county of 5 Westchester and State of New York, have invented new and useful Improvements in Wall-Paper Machines, of which the following is a full, clear, and exact description.

The object of the invention is to provide 10 certain new and useful improvements in wall paper machines whereby a highly ornamental effect on the wall paper is produced with the use of simple and comparatively inexpensive means and without the use of cut 15 printing rolls.

In order to produce the desired result, use is made of a printing roll coacting with the 20 impression cylinder to make an impression on the paper passing between the printing roll and the cylinder, the printing roll being provided on its peripheral face with line or narrow 25 stripe printing means, and the printing roll being mounted to turn in unison with the impression cylinder and to travel lengthwise, and means imparting a lengthwise traveling motion to the said printing roll to cause the printing means thereof to print undulating lines on the paper.

A practical embodiment of the invention 30 is represented in the accompanying drawings forming a part of this specification, in which similar characters of reference indicate corresponding parts in all the views.

Figure 1 is a side elevation of a wall paper 35 printing machine provided with two printing rolls, of which one is mounted to travel lengthwise to produce wavy or undulating lines on the paper, and the other printing roll is non-shiftable to produce 40 straight lines or stripes on the paper;

Fig. 2 is an elevation of a portion of the left hand side of the wall paper printing machine with the frame shown in section;

Fig. 3 is an enlarged cross section of the 45 means for imparting a bodily traveling movement to the printing roll;

Fig. 4 is a face view of the cam;

Fig. 5 is a face view of the paper provided 50 with straight lines or narrow stripes produced by the non-shifting printing roll;

Fig. 6 is a similar view of the paper provided with an additional imprint of wavy or undulating lines or stripes;

Fig. 7 is a similar view of the paper provided 55 with an additional imprint of straight lines on running the paper a second time

through the machine but in a reverse direction; and

Fig. 8 is a similar view of the paper provided with another imprint of wavy or undulating lines or stripes produced during 60 the second run of the paper through the machine.

The impression cylinder 10 of the wall paper machine has its shaft 11 journaled in 65 suitable bearings arranged on the main frame 12. One end of the shaft 11 (see Fig. 2) is provided with a gear wheel 13 in mesh with a pinion 14 secured on a shaft 15 carrying the printing roll 16 which coacts 70 with the impression cylinder 10 to make an impression on the paper passing around the impression cylinder 10 in the usual manner. The printing roll 16 is provided on its peripheral face with annular line or narrow 75 stripe printing means 17 arranged close together and in the form of ridges or disks in contact with the inking web 20 which passes around the usual guide rollers 21 and is in contact with the fountain roller 22 of a fountain 80 23 for supplying the ink to the printing means 17 on the peripheral face of the printing roll 16.

The printing roll shaft 15 is mounted to turn in bearings 25 arranged on the main 85 frame 12, and the said printing roll shaft 15 is also arranged to travel bodily in a lengthwise direction to cause the printing means 17 to print undulating lines on the paper. In order to impart this bodily movement to the printing roll 16 the following 90 arrangement is made: A sleeve 30 having a bore 31, larger in diameter than that of the shaft 15, engages the shaft and is provided at one end with an interior annular ridge or 95 flange 32 rounded off and seated on the peripheral face of the shaft 15. The other end of the sleeve 30 is provided with a series of set screws 33, preferably four in number and spaced equal distances apart to allow of 100 fastening the sleeve 30 to the shaft 15 with the axis of the sleeve at an angle to the axis of the shaft 15, as plainly indicated in Figs. 2 and 3. The sleeve 30 is provided, at the end having the ridge 32, with a flange 34 extending between two rollers 40 and 41 journaled on studs 42, 43 depending from a bracket 44 fastened to the main frame 12. The flange 34 extends at a right angle to the axis of the sleeve 30 and hence is inclined 105 relative to the shaft 15, and when the latter is rotated then the flange 34 on passing be-

110

tween the rollers 40 and 41 is given a wabbling movement and consequently the shaft 15 and its printing roll 16 are caused to travel bodily in a lengthwise direction, that is, first to one side, then back again, during each revolution of the shaft 15. It will be noticed that this traveling motion can be increased or diminished by adjusting the sleeve 30 by the set screws 33 correspondingly on the shaft 15 to give more or less inclination to the flange 34 relative to the shaft 15.

A second printing roll 50 similar to the printing roll 16 is used in conjunction with the impression cylinder 10 to print straight lines on the paper. This printing roll 50 has printing means 17 the same as the roll 16, and the shaft 51 of this printing roll 50 is driven from the gear wheel 13 but receives no bodily lengthwise traveling movement. From the foregoing it will be seen that the printing roll 50 prints straight lines on the paper while the roll 16 prints wavy or undulating lines on the said paper crossing or intersecting the straight lines, as indicated in Figs. 5, 6 and 7.

Two or more printing rolls 16 and two or more printing rolls 50 may be used, but in practice the two rolls 16 and 50 are sufficient to produce the desired variegated effect on the paper, especially when using different colors for the two printing rolls 16 and 50.

If desired, the paper may be run twice through the wall paper machine to provide double impressions from the printing rolls 16 and 50 to heighten the variegated effect, it being understood that for the second impressions the paper is run through the machine in a reverse direction.

It is understood that the printing roll 16 traverses the face of the impression cylinder 10 a distance in each direction exceeding that between adjacent line printing means on the printing roll 50 so that the undulating lines or stripes printed on the paper by the printing roll 16 cross one, two or more of the straight lines or stripes printed by the other printing roll 50.

It is well known that the paper in passing around the impression cylinder 10 occasionally shifts in a transverse direction and hence the corresponding portions of the straight lines or stripes produced by the printing roll 50 during this shifting of the paper are out of parallelism with the edges of the paper and the undulating lines or stripes produced by the printing roll now cross different straight lines or stripes thus varying the design and enhancing the effect thereof. Thus the out-of-alinement position of the paper on the printing cylinder and which is detrimental to the production of a many colored design as now generally produced becomes a desirable factor and assists in effectively varying the design produced by the

machine. From the foregoing it will be seen that the two printing rolls 16 and 50 coat with the impression cylinder 10 to produce a highly ornamental design which practically varies throughout the length of 70 the wall paper. It will also be noted that the two printing rolls 16 and 50 are not in registering relation one to the other and hence the machine can be run at a high rate of speed and requires little attention on 75 the part of the operator as the non-registering of the printing rolls 16 and 50 forms a desirable factor instead of a detrimental one.

Having thus described my invention, I claim as new and desire to secure by Letters 80 Patent:—

1. In a wall paper printing machine, the combination of an impression cylinder, a printing roll coating with the said impression cylinder to make an impression on 85 the paper passing around the impression cylinder, the printing roll being provided on its peripheral face with line or stripe printing means and the printing roll being mounted to turn and to travel lengthwise, and means imparting a lengthwise traveling motion to the said printing roll a distance in excess of the distance between adjacent line or stripe printing means to cause the printing means thereof to print undulating lines 95 or stripes on the paper passing around the impression roll.

2. In a wall paper printing machine, the combination of an impression roll, a printing roll coating with the said impression 100 roll to make an impression on the paper passing around the impression roll, the said printing roll being provided on its peripheral face with line or stripe printing means, the said printing roll having a shaft 105 rotating in unison with the said impression roll and being mounted to slide lengthwise, a cam held on the said shaft, and fixed means engaging the said cam to impart a sliding motion to the rotating shaft and the printing roll a distance in excess of the distance between adjacent line or stripe printing means to cause the latter to print undulating lines 110 or stripes on the paper.

3. In a wall paper printing machine, the 115 combination of an impression roll, a printing roll coating with the said impression roll to make an impression on the paper passing around the impression roll, the said printing roll being provided on its peripheral face with line or stripe printing means, the said printing roll having a shaft 120 rotating in unison with the said impression roll and being mounted to slide lengthwise, a sleeve on the said shaft and provided at 125 one end with an internal annular bearing ridge engaging the shaft, an external flange integral on the sleeve opposite the ridge, set screws screwing in the other end of the sleeve against the shaft to allow of setting 130

the sleeve at an angle to the shaft, a fixed bracket, and spaced rollers journaled on the said bracket and engaging the flange between them.

5 4. In a wall paper machine, the combination of a revoluble impression cylinder, two printing rolls rotating in unison with the said impression cylinder and provided at their peripheral faces with line or stripe printing means to print lines on the paper passing between the impression cylinder and the said printing roll, one of the printing rolls being held against lengthwise movement and the other being mounted to slide lengthwise, and means engaging the said printing roll to impart a lengthwise sliding motion to this roll and alternately in opposite directions.

5. In a wall paper machine, the combination of a revoluble impression cylinder, two printing rolls rotating in unison with the said impression cylinder and provided at their peripheral faces with line or stripe printing means to print lines on the paper passing between the impression cylinder and the said printing roll, one of the printing rolls being held against lengthwise movement and the other being mounted to slide lengthwise, a sleeve adjustably held at an angle on the said slidable printing roll and provided with an annular flange, a pair of rollers engaging the opposite sides of the said flange, and a fixed bracket on which the said rollers are journaled. 20 25 30
